UNITED STATES PATENT OFFICE.

WILLIAM T. RUTH, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

ROCK-CRUSHER.

1,202,591.

Specification of Letters Patent. Patented Oct. 24, 1916.

Application filed April 7, 1916. Serial No. 89,531.

To all whom it may concern:

Be it known that I, WILLIAM T. RUTH, a citizen of the United States, residing at Kennett Square, county of Chester, and State 5 of Pennsylvania, have invented a new and useful Improvement in Rock-Crushers, of which the following is a full, clear, and exact description, reference being had to the accompanying drawings, which form a part 10 of this specification.

In the operation of rock crushers it frequently happens that a large or excessively hard lump or mass of material becomes wedged between the jaws of the crusher in 15 such a way as to resist crushing and lock the jaws from movement and throw the crusher out of operation. It then becomes necessary to dig out the mass of material lodged between the jaws and sometimes to 20 use explosives to blast out the material or destroy the toggle connecting the movable jaw and its actuating tumbler. Thus there is caused serious loss of time and often damage to the crusher.

25 The object of my invention is to provide means to dislodge or eject the material wedged between the jaws by so constructing the crusher that the distance between the jaws may be automatically increased beyond 30 its maximum during normal operation of the machine, thereby allowing the material wedged between the jaws to drop out. In the specific embodiment of my invention herein set forth, this result is accomplished 35 by giving to the tumbler, in addition to its ordinary movement of oscillation, an additional retractive movement, whereby the strut or toggle connecting the tumbler and movable jaw will become detached, allowing 40 the movable jaw to swing away from the fixed jaw to such an extent as to permit the entire contents of the jaw pocket to drop out. This embodiment of the invention also comprises means to hold the movable jaw 45 stationary during this special retractive movement of the tumbler, so as to prevent the movable jaw following the tumbler in its said retractive movement, thereby insuring the release of the toggle.

50 In the drawings, which show this preferred specific embodiment of my invention Figure 1 is a vertical transverse section through the crusher. Fig. 2 is a detail view of the movable jaw-holding contrivance. 55 Fig. 3 is a section on the line 3—3 of Fig. 1,

with certain parts omitted. Fig. 4 is a front view of the crusher looking in the direction of the arrow 4, Fig. 1.

The main elements of the crusher shown in the drawings are old and well known, 60 and will be described in a general way but not in precise detail. Between the side plates *a* is secured a fixed jaw *b* faced with a hardened die *c*. The side plates *a* carry bearings for the shaft *d* from which is suspended 65 the pendent swinging jaw *e* faced with a hardened die *f*. The side plates also carry bearings for the shaft from which is suspended, in the manner hereinafter described, the tumbler lever *h*. Opposite faces of the 70 movable jaw and tumbler lever are recessed to receive toggle seats *j* and *j'* between which is held, by the weight of the movable jaw *e* the strut or toggle *i*. On the main shaft *k*, which also extends between the side 75 plates, are the fly wheel *l* and the cams *m*, which, through the medium of the roller *n*, actuates the tumbler *h*. *o* are the tension rods, which operate to assist the normal 80 opening movement of the movable jaw, insuring that it shall follow the tumbler lever in the back stroke of its oscillating movement. These rods are, at their forward ends, attached to ears *p* at opposite ends of the movable jaw.

85 The above construction, which, as above stated, is old and well known, is modified by me, to accomplish the results hereinbefore set out, in the following manner. Within the circular bearing face of the tumbler 90 lever *h* is a sleeve *q* within which is an eccentrically mounted shaft *r*, which may be seen best in Fig. 3. Secured to the outer end of this shaft is an arm *s*, which is normally in the full line position shown in 95 Fig. 3, its free end being orificed to receive a pin *t* which passes also through a hole in a bracket *u* secured to one of the side plates. Thus the eccentric is normally held stationary, so that, in the normal operation of the 100 crusher, the tumbler lever is given the usual simple movement of oscillation on a fixed axis. I also provide the following connection, normally not in use, between the two jaws; its purpose being hereinafter described. Two hooked rods *v*, one of which is shown in Fig. 2, pass through between ears *w* under opposite ends of the fixed jaw, the hooked ends entering orifices in the ears 105 *p*. The end of each rod is threaded to 110

receive a nut *w*, which, when tightened against the rear of the corresponding ear *w*, holds the two jaws in fixed relation. Assume that some uncrushable lump or mass becomes wedged between the jaws so as to render the crusher inoperative. The operator then proceeds as follows: The holding rods *v* are applied as above described. The pin *t* is removed to free the arm *s*, which is then moved from the full-line position shown in Fig. 1 to the dotted line position, thereby turning the eccentric shaft and retracting the pivoted end of the tumbler lever *h*. This permits the toggle *i* to drop out from between the tumbler lever and the movable jaw. The rods *v* are then removed, allowing the movable jaw to swing away from the fixed jaw far enough to allow all the material contained between the jaws to drop out.

To restore the crusher to operative position, the lower end of the movable jaw is swung toward the fixed jaw, the rods *v* are replaced, the toggle *i* is held by hand in its normal position, and the arm *s* is swung into its full time position, causing the pivoted end of the tumbler lever *h* to move toward the movable jaw to the extent required to hold the toggle *i* between the grooves in the toggle seats *i* and *i'*. The rods *v* are then again removed and the crusher is restored to operative position. This mode of removing the contents of the crusher pocket is not only highly expeditious, but is attended with no danger whatever to any of the machine parts.

Having now fully described my invention, what I claim and desire to protect by Letters Patent is:

1. In a rock crusher, the combination with the two jaws, of actuating mechanism adapted to impart to one of the jaws a reciprocating movement, and means to disrupt the operative connection between the driving mechanism and the reciprocating jaw to allow the latter to swing away from the fixed jaw and permit the material between the jaws to drop out.

2. In a rock crusher, the combination with the two jaws, one of which is adapted to swing back and forth toward the other jaw, actuating mechanism adapted to so oscillate the jaw between positions inclined at different angles to, and on one side of, a vertical line passing through its axis of oscillation, and means to disrupt the operative connection between the driving mechanism and the oscillating jaw to allow the latter to drop toward said vertical line and open the pocket between the jaws.

3. In a rock crusher, the combination with the two jaws, of actuating mechanism adapted to impart to one of the jaws a reciprocating movement, normally inoperative means adapted to hold the jaws in definite relation, and means to disrupt the operative connec-

tion between the driving mechanism and the reciprocating jaw, thereby permitting the latter, when said holding means is rendered inoperative, to swing away from the fixed jaw.

4. In a rock crusher, the combination with the fixed jaw and a pendent jaw adapted to swing, of actuating mechanism adapted to oscillate the pendent jaw between positions inclined at different angles to, and on one side of, a vertical line passing through its pivot, normally inoperative means adapted to be applied to hold the pendent jaw, independent of the actuating mechanism, from dropping toward a vertical position, and means to disrupt the operative connection between the driving mechanism and the pendent jaw, thereby permitting the pendent jaw to swing toward a vertical position when said holding means is rendered inoperative.

5. In a rock crusher, the combination with two jaws, of a driving shaft, a chain of elements between the driving shaft and one of said jaws adapted normally to swing such jaw toward and from the other jaw, and means to remove one of said elements of the chain of actuating mechanism, thereby allowing the swinging jaw to move an abnormal distance from the other jaw and thus permit the discharge or removal of material wedged between the jaws.

6. In a rock crusher, the combination with two jaws, of a driving shaft, a chain of elements between the driving shaft and one of said jaws adapted normally to swing such jaw toward and from the other jaw, and means independent of the driving shaft to actuate one of said elements to permit the removal of another element, thereby destroying the normally operative driving connection to the swinging jaw and allowing it to be retracted an abnormal distance from the other jaw.

7. In a rock crusher, the combination with the two jaws, of an oscillating tumbler and means to actuate the same, a removable operative connection between the tumbler and one of the jaws, normally inoperative means to hold the jaws in definite relation, and means to impart to the tumbler a movement of retraction independent of its normal oscillating movement, thereby permitting the removal of the operative connection between the tumbler and its actuated jaw and allowing said jaw, after said holding means is rendered inoperative, to drop away from the other jaw.

8. In a rock crusher, the combination with the fixed jaw and the movable jaw, of a tumbler and means to oscillate the same, a movable toggle between the tumbler and the movable jaw, a detachable device adapted to hold the two jaws in definite relation, and means to impart to the tumbler a movement of retraction independent of

- its normal oscillating movement, thereby, after said detachable connection is applied, permitting the detachment of the toggle by said retraction of the tumbler and then, 5 after said detachable connection is removed, permitting the swinging of the movable jaw away from the fixed jaw.
9. In a rock crusher, the combination with the two jaws, of a tumbler, a normally stationary eccentric on which the tumbler swings, means to oscillate the tumbler, a removable toggle between the tumbler and the movable jaw, means to hold one jaw from swinging away from the other jaw, 10 and means to turn the eccentric, thereby retracting the pivoted end of the tumbler, detaching the toggle and allowing one jaw to swing away from the other jaw after the removal of said holding means.
10. In a rock crusher, the combination with the fixed jaw and the movable jaw, of an oscillating tumbler and means to actuate the same, a removable toggle between the tumbler and the movable jaw, a hooked rod 15 adapted to be applied to the two jaws to hold them in fixed relation, and means to impart to the tumbler a movement of retraction independent of its normal oscillating movement, thereby, after said removable rod is applied, permitting the detachment of the toggle, and after said removable rod is removed permitting the automatic separation of the jaw. 20
11. In a rock crusher, the combination with the fixed jaw and the movable jaw, of a tumbler, a normally stationary eccentric on which the tumbler swings, means to oscillate the tumbler, a toggle loosely connecting the tumbler and movable jaw and held in place by the weight of the latter, 25 a detachable hooked rod adapted to be applied to the jaws to hold them in fixed relation, and means to turn the eccentric. 30

In testimony of which invention, I have hereunto set my hand, at Philada. Penna., 40 on this 6th day of April, 1916.

WILLIAM T. RUTH.
